EXPANSION JOINT

John L. Herwood, Pittsburgh, Pa., assignor to
 Aluminum Company of America, Pittsburgh,
 Pa., a corporation of Pennsylvania

Application December 13, 1934, Serial No. 757,341

5 Claims. (Cl. 189—75)

This invention relates to expansion joints. It relates particularly to expansion joints in concrete structures and the joining of metal and concrete sections. By the term "concrete" is meant both monolithic and masonry forms of rigid cement or cemented construction.

It has become a general practice in designing structures of appreciable size of concrete or concrete and metal construction to provide for expansion or movement of various sections or portions within the structure in a definite manner by the proper placement of yieldable portions or suitable clearances, referred to collectively as expansion joints, so as to avoid cracking or straining the entire structure by the independent movement or expansion of one or more individual sections. There is also a growing tendency to employ metal in exterior surfaces of concrete structures to a larger extent in the form of large metal framed windows or large metal spandrels. This change in construction has increased the difficulty of securing a satisfactory and lasting joint between sections which is capable not only of absorbing the maximum expansive movement in the building due to temperature changes, wind movement or earth tremors, but also the differential expansion between sections of different materials.

An object of my invention is to provide an improved expansion joint which will allow for the free movement of individual sections in the structure. Another object is to provide an expansion joint for concrete structures which will maintain a weather-proof and water-proof seal and allow a substantial movement of the sections joined. A further object is to provide an improved expansion joint for concrete and metal sections. These and other objects will be apparent from the detailed description and the drawings which form a part of this specification.

The expansion joint contemplated by this invention provides a means of joining sections in a structure in a manner which maintains a weather-proof, water-tight seal and at the same time provides for free movement in a predetermined direction of the individual sections joined. The joint or seal is perfected through the novel application of weather-proof sealing compounds, for example asphaltic base compounds. The seal is accomplished by holding a layer of sealing compound, such as a plastic layer of suitable material, firmly on one side of a serrated surface and contacting the other side of the plastic layer with a plane surface which, if the elastic limit of the sealing material is exceeded by an opposite

movement of the two surfaces, can move in contact with the sealing material without affecting the seal or transporting the sealing material. It has been found that one practical embodiment of this invention consists in providing a recess with serrated interior wall surfaces in the form of a channel or socket in the abutting surface of one section to be joined, and a plane-surfaced tongue-like male member on the oppositely disposed abutting surface projecting into the serrated socket or channel and separated from it by a layer of plastic sealing material. The embodiment of this invention can assume many forms and modifications. For the purposes of explanation, two embodiments of this invention will be described, one for joining metal and concrete sections and the other for joining two concrete sections. These are illustrated in the drawings, in which:

Fig. 1 is a horizontal sectional view showing a metal window frame yieldably supported in a concrete wall;

Fig. 2 is a fragmentary vertical sectional view taken on the line II—II of Fig. 1;

Fig. 3 is a fragmentary horizontal sectional view showing a portion of Fig. 1 to an enlarged scale;

Fig. 4 is a horizontal sectional view showing a modified form of my improved expansion joint connecting two concrete sections; and

Fig. 5 is a perspective view of a metal sealing strip employed in the modification shown in Fig. 4.

Like numerals are used throughout the various drawings to denote like parts.

Referring to Figs. 1, 2 and 3, a concrete section 6 is provided with a channel member 7 set in its body with the opening flush with the surface of the section. The interior side surfaces of the channel are serrated parallel to its length. The channel is bridged at intervals according to the size and weight of the window or other assembly to be supported by bars 8 set in the concrete. The frame is supported by the bars by means of the subframe plate member 9 which projects into the channel. The member 9 is provided with L-shaped slots 10 which engage the bars 8 as shown in Fig. 2. These L-shaped slots 10 provide a means of positively supporting the frame from the bars and permit a horizontal and vertical expansive movement by reason of the L portion of each slot being substantially wider than the supporting bar. The space or clearance between members 7 and 9 is filled with a viscous sealing compound 11. The serrations 12 substantially prevent the extrusion of the sealing

material from the joint even after long continued working due to the relative movement of the serrated and plane-surfaced members 7 and 9, respectively.

5 The erection and assembly of this expansion joint is relatively simple and easily carried out. It is customary to fasten member 7 to the concrete form in accurate position, as by nailing, before the concrete is poured. The nails may be 10 cut off for removal of the form, the remaining nail heads, for example, being shown at 13 in Fig. 3. The desired number of supporting bars 8 are also positioned by insertion through apertures 14 in the channel member 7. After the 15 concrete has been poured and set and the forms have been stripped the channel is filled or partially filled with a plastic sealing compound. This material, in practice, is usually applied by means of a pneumatic gun, referred to in the art 20 as a "putty gun". However, it may be applied in any convenient manner. The projecting plate member 9 of the metal frame assembly is inserted in the channel, and the L-shaped slots 10 drop over the bars 8. A clearance space 25 rounding the member 9 in the channel 7 is completely filled with plastic sealing compound 11 previously applied to the channel. The L portions of the slots in which the bars rest are enlarged to substantially greater dimensions than 30 the bars, as illustrated in Fig. 2. The window frame assembly may now be completed. In this type of construction it is possible to use any type 35 of window sash construction and sash-operating mechanism desired provided means are adopted for securing such sash and mechanism to the sub-frame member. If desired, the L-shaped slots and corresponding supporting bars may be omitted from the horizontal portion of the seal, that is, top and bottom, owing to the fact that the weight 40 is carried by the vertical side bar members.

40 A modification of this invention is shown in Fig. 4 and is designed to meet the particular needs of joining two concrete sections. The sealing members are substantially identical with the constructions shown in Figs. 1 and 3, but in addition modifications have been made which are desirable in connecting concrete sections. The anchorage of the channel member 7 in the concrete section is preferably strengthened by providing a broad flange 16 at the inner end of the channel member. 45 Flanges 16 extend outwardly from the channel of member 7 along the surface of the concrete section. These flanges 16 have recessed portions 17 which are provided with serrations 18 running 50 parallel with the joint, as shown in Fig. 4.

55 The male member 9¹, where concrete sections are to be joined, is preferably made integral with a shape otherwise similar to the female member 7, and similar reference numerals have been used to denote like parts thereof. The member 9¹ is hereinafter referred to as a male member.

60 The members are positioned accurately and fastened to the form before the concrete is poured. In case the concrete sections are poured in place, the female member may be secured in accurate position to the inner side of the form for one abutting surface and the concrete subsequently poured and allowed to set. The form may then be stripped off or at least removed 65 from the abutting surface and the channel of the female member filled with plastic sealing compound. The male member is placed in position, the projecting portion 9¹ being forced into the plastic filled channel. A form for the second concrete sections is then erected overlapping to

some extent the first section. The male member is securely fastened, as by wire to the form, within the form, in desired position and a spacer of desired thickness, usually cork board, placed on each side of the projecting member 9¹ covering 5 the abutting face. The second section is then poured. When the concrete is set and the form removed, the spacer is easily removed. While this procedure is a preferred method of erection, it will be understood that any suitable 10 method may be used.

15 The metallic sealing strip 20 for sealing the clearance space between the abutting sections is shown in perspective in Fig. 5 in a manner which clearly shows its construction. This strip is 20 formed of resilient sheet metal. The actual sealing portion 21 is shaped by folding the sheet upon itself in either direction, forming a head. The under surface of this head which contacts the surface of the sections 6 is formed with a substantially flat surface. The upper surface is commonly formed with a flat surface but may be formed in a semi-circle or other form appropriate for use in the general architectural design of the structure. The sheet is further shaped to 25 form a web portion 22 and outwardly projecting locking members 23. The width of the head is, of course, somewhat greater than the maximum clearance space to be sealed. The depth of the web portions 22 is sufficient to position the locking 30 members 23 within the serrated area of the recesses 17 formed by the oppositely disposed flanges 16 of the members 7 and 9¹. The locking portions 23 are of sufficient width to fit in the serrations 18 of the recesses with spring tension. 35 The sealing strip is positioned by inserting the web and locking members in the clearance between the concrete sections 6. During the insertion the locking members 23 are compressed towards the web 22. When the strip enters the 40 recesses 17 the locking members 23 spring outwardly and lock in the serrations. A tension is established through the pressure of the locking members against the serrated recess walls, which tends to hold the sealing head 21 in close contact 45 with the exterior surfaces of the sections joined.

45 The sealing compound herein referred to may be any one of the many compounds commonly used. These compounds are usually of the asphalt base type and are of a heavy, viscous liquid 50 or plastic consistency. In many respects they resemble ordinary pitch and sometimes contain large amounts of this material. The type of sealing compound preferred for use in this invention is of a plastic gummy consistency.

55 The metal parts of this improved expansion joint may be formed of any metal that can be economically formed by the process of extrusion, such as aluminum, copper or zinc. Due to its inherent light weight and resistance to atmospheric 60 corrosion, aluminum is preferred. In actual practice it has been found desirable, especially in the case of very long joints, to erect the female members in several sections rather than in one continuous piece. In case of joining concrete sections, this also applies to the male members. This simplifies erection and obviates the danger of difficulty owing to the differential expansion 65 between the metal members and the concrete.

70 This invention finds a wide application especially in the construction of concrete and metal buildings. The two modifications herein described possess additional individual advantages which greatly enhance their value. For ex- 75

ample, the installation of metal window frames after the manner illustrated in Figs. 1, 2 and 3 can be carried out from the interior of the building without necessitating the erection of outside scaffolding. Moreover, in this case the yieldable support makes ample provision for expansion, and very large metal framed windows may be successfully used without glass breakage due to unforeseen building movement. The modification illustrated in Figs. 4 and 5 not only gives a yieldable weatherproof joint for connecting concrete sections but also provides in a metallic sealing strip a means of rendering the joint inconspicuous by the proper coloring and/or forming of the head of the strip, or a means of breaking, in an effective manner with vertical panel lines, large expanses of concrete wall and performing an important function in the architectural treatment of the structure.

Having described my invention in accurate detail and shown how it works, what I claim is:

1. An improved expansion joint for yieldably joining sections of a structure, comprising, in two abutting sections, a channel-like female member positioned in one abutting section and a male member oppositely disposed in the other abutting section and projecting into the channel of said female member, at least one of said members being provided with a serrated surface, and a plastic sealing compound filling the space between said members.

2. An improved expansion joint for yieldably joining sections of a structure, comprising, in two abutting sections, a serrated channel-like female member positioned in one abutting section and a plane-surfaced male member disposed oppositely in the other abutting section and projecting into the serrated channel of said female member, and a plastic sealing compound filling the space between said male member and the serrated surface of said female member.

3. An improved expansion joint for joining abutting concrete and metal sections in a structure, comprising a serrated channel-like female

member positioned in the concrete section, bars positioned in the concrete piercing the channel at predetermined intervals, a plate male member protruding from the metal section provided with L-shaped slots spaced at intervals corresponding with the bars in said channel, the L portion of the slots being of substantially greater dimensions than said bars, said plate projecting into said channel and surrounding said bars in the L-shaped portion of the slots, and a plastic sealing compound filling the space between the male member and the serrated surface of the female member.

4. An expansion joint of the type described, comprising, in two adjacent concrete sections, a female member imbedded in the surface of one section, said female member having a channel disposed parallel to the expansive movement, the side wall surface of said channel being provided with a plurality of serrations extending the length of the joint, a male member imbedded in the adjacent section and extending within said female member and being separated from the serrated walls of said female channel portion by a plastic material, said members being provided with flanges extending outwardly along the adjacent surfaces of said concrete sections, said flanges having recessed portions provided with serrations, and a metallic sealing strip insertable from the surfaces of the structure adapted to be held in tight-pressed engagement with the structure surface by a spring-pressed engagement with the serrations in said recesses.

5. In an expansion joint assembly, yieldably joining sections of a structure wherein a recess is formed in the surfaces of the sections with oppositely disposed serrated surfaces parallel to the joint, a sealing strip insertable from the surface of the structure adapted to be held in tight-pressed engagement with the structure surface by a spring-pressed engagement with the serrations in said recesses.

JOHN L. HERWOOD.
